Primary Examiner — Paula Greene(74) *Attorney, Agent, or Firm* — Howard & Howard Attorneys PLLC(57) **CLAIM**

The ornamental design for a wireless transmitter, as shown and described.

DESCRIPTION

FIG. 1 is a perspective view of the wireless transmitter;
FIG. 2 is a front view of the wireless transmitter shown in FIG. 1;
FIG. 3 is a rear view of the wireless transmitter shown in FIG. 1;
FIG. 4 is a side view of the wireless transmitter shown in FIG. 1;

FIG. 5 is a side view of the opposing side of the wireless transmitter shown in FIG. 1;
FIG. 6 is a top view of the wireless transmitter shown in FIG. 1; and,

FIG. 7 is a bottom view of the wireless transmitter shown in FIG. 1.

The broken lines in the Figs showing portions of the wireless transmitter or portions thereof form no part of the claimed design.
